J. SACHS

ELECTRICAL CONNECTION MEANS

Filed July 29, 1922

UNITED STATES PATENT OFFICE.

JOSEPH SACHS, OF HARTFORD, CONNECTICUT.

ELECTRICAL CONNECTION MEANS.

Application filed July 29, 1922. Serial No. 578,340.

To all whom it may concern:

Be it known that I, JOSEPH SACHS, a citizen of the United States, residing at Hartford, in the county of Hartford and State of Connecticut, have invented a new and useful Improvement in Electrical Connection Means, of which the following is a specification.

This invention relates to the construction and arrangement of the means supplied to switch and cut-out blocks for making branch connections with main wires of electrical circuits. The mains are ordinarily heavy, stiff insulating wires which are difficult to bend and loop. Safety requires that wires of different polarity be spaced or otherwise insulated from each other.

The object of the present invention is to provide switch blocks, cut-out blocks and similar devices with means which facilitates the making of branch connections with mains and which at the same time ensures suitable separation of the wires.

This object is attained by extending the conductors to be connected with the mains beyond the edge of the base to which the conductors are attached, and positioning the terminals of the conductors for the wires of different polarity in different planes with relation to the base, so that the main wires may be carried to the bussing terminals by simple, easily made bends, which terminals being at different levels permit the necessary separation of the wires to ensure safety without excessive bending.

In the accompanying drawings Figure 1 shows a plan of a three wire switch and cut-out block with meter testing connections, that is provided with branch connecting means arranged according to this invention. Fig. 2 shows a front elevation of the block. Fig. 3 shows an edge view of one connection piece. Fig. 4 shows an edge view of another connection piece.

The invention is applicable to branch blocks in general. These blocks may have two or three wire connections, which connections may be solid links, or may include fusing or switching means, or a combination of such means. The block illustrated has a base 1 of insulating material mounted upon which are two fuses 2 and three switches 3. The fuses may be any desired type, those shown being ordinary screw plug fuses, and the switches may be any desired character, those shown being common knife blades.

At the upper edge of the base the switch blades are illustrated as connected with terminals 4. One of the terminals of each of the fuses is connected with a terminal 5 at the upper edge of the base. In the block exemplified the outer pairs of the upper terminals are designed to be connected with meter leads in the customary manner. At the lower edge of the base the switch blades are connected with terminals 6, and the other of the terminals of each of the fuses is connected with a terminal 7 at the lower edge of the base. The two outermost terminals at the lower edge of the base are adapted to be connected with the load wires whereas the three inner terminals at the lower edge of the base are designed to be connected with the main wires. The terminals may merely be provided with wire binding screws 8, or with binding screws and meter testing lugs 9, or they may be provided with wire clamps 10, the specific form of means for attaching the circuit wires being immaterial.

In carrying out this invention the lower switch terminals 6 are, in the form illustrated, substantially flat plates located in recesses 11 in the base so that their outer ends are positioned a little above the lower face of the base at one level, whereas the lower terminals 7 connected with the fuses are bent upwardly and applied to the base so that their outer ends are positioned at a higher level than the switch terminals. Furthermore the fuse terminals 7 and the terminal 6 of the neutral line, besides being at different levels, are projected beyond the edge of the base. Of course the neutral path could be omitted from the structure if the block was to be used for two wire service. As a result of extending the terminals of the connectors for the mains beyond the edge of the base, and also positioning the terminals for different polarities at different levels, the circuit wires may be conveniently connected without necessitating distortion of the wires, that is, the connections may be made without sharply looping in and out and up and down the stiff insulating wires to bring them up to the clamping terminals, and to separate them so that wires of different polarity or potential will not be in contact or close proximity.

This invention is particularly serviceable when the blocks are to be enclosed in protecting boxes as the connections can be

safely made in less space than with prior arrangements, which enables the boxes to be made smaller with a resultant saving in cost.

The invention claimed is:—

- 5 1. A branch block having conducting paths with terminals provided with wire attaching means, said wire attaching means at one end of the paths extending beyond the edge of the block and positioned at different levels, whereby circuit wires may be readily looped to said attaching means and those of different polarity suitably separated without excessive bending of the wires.
- 10 2. A branch block having conducting paths with bussing terminals at one end, said terminals extending beyond the edge of the block at different levels.
- 15 3. A branch block having conducting paths with bussing terminals at one end, said terminals being positioned at different levels.
- 20 4. A branch block having conducting paths containing fuses and conducting paths

containing switches, and terminals for said paths provided with wire attaching means, 25 the wire attaching means for said fuse paths being in a different plane from the wire attaching means for said switching paths.

5. A branch block having conducting paths with fusing means and conducting 30 paths with switching means, the terminals for said paths being provided with wire attaching means, said wire attaching means at one end of the paths projecting beyond the edge of the block and positioned at different 35 levels.

6. A branch block having conducting paths with fusing means and conducting paths with switching means, and terminals for said paths provided with wire attaching 40 means, said wire attaching means for the fused paths being at one level and said wire attaching means for the switching paths being at a different level.

JOSEPH SACHS.
